UNITED STATES PATENT OFFICE.

GARRET S. MOTT, OF PHILADELPHIA, PENNSYLVANIA.

DUPLEX TELEGRAPH.

SPECIFICATION forming part of Letters Patent No. 243,288, dated June 21, 1881.

Application filed September 30, 1880. (No model.)

To all whom it may concern:

Be it known that I, GARRET S. MOTT, a citizen of the United States, and a resident of Philadelphia, Pennsylvania, have invented an Improved Duplex-Telegraph System, of which the following is a specification.

My invention relates to certain improvements in that class of duplex-telegraph systems in which an equalizing or equating battery and circuit is combined with the main battery, transmitter, relay, and circuits at each station, in order to prevent the home main battery from affecting the home relay on the opening or closing of the transmitter; and the objects of my invention are to simplify and improve the operation and construction of the system, and to insure the presentation to the incoming current at each station of the same amount of resistance under all circumstances, irrespective of the changes of circuit. These objects I attain in the manner I will proceed to describe, reference being had to the accompanying drawings, in which—

Figure 1 is a diagram illustrating my improved system of duplex telegraphy, and Fig. 2 a diagram of a modified arrangement. Each of these diagrams illustrates the arrangement of transmitter, batteries, resistance-coils, and circuits at only one station, but as the same arrangement exists at the other station it has not been deemed necessary to illustrate it.

Referring to Fig. 1, T is the transmitter; R, an ordinary relay; M B, the main battery; E B, the equalizing-battery; R h, an adjustable rheostat or resistance coil or box, and G the ground or earth connection.

The armature of the transmitter T consists of a lever, A, pivoted at p, and having its opposite ends insulated from each other, and to each is secured a flat spring, s, (s') on an insulated support, the free end of the spring, when in its normal position, (as indicated on the diagram,) bearing against the inner face of the hook-shaped end a (a') of the lever, while an adjacent stop, m, (m'), is adapted to bear on the spring and break its contact with the end a (a') of the lever-armature when the latter is attracted by the electro-magnets of the transmitter. The line-wire is connected with the stop m through the wire b and the main battery, and with the end a' of the armature-lever through

the wire b', while the spring s' is connected, through the wires d d', with the relay R, which is grounded through the wire d'. The equalizing-battery E B is connected with the stop m through the wire e, and the spring s is connected, through the wire f, rheostat R h, and wire d', with the relay, while the end a of the armature-lever is connected with the ground through the wires e' and f', a ground-connection for the battery E B being made through the wires e' and f'. When the transmitter T is open—that is, when its armature is not attracted to the electro-magnets—the incoming current from the line goes to the relay through the wire b', end a' of the armature-lever, spring s', and wires d d', and thence to the ground, while the main battery M B, having no connection through the stop m', is thrown out of circuit. At the same time the equalizing-battery E B, having no connection through the stop m, is also out of circuit. On the other hand, when the transmitter is closed the incoming current goes to the relay R through the battery M B, wire b, stop m', spring s', and wires d d', and thence to earth.

In order to neutralize the effect on the relay of the current from the main battery M B at the home station, as it flows through the relay to earth on the closing of the home transmitter, the action of the equalizing-battery is brought into play. At the same moment that the attraction of the armature A to the magnets of the transmitter brings the stop m' into contact with the spring s' and breaks the contact between the arm a' and spring s' the spring s at the opposite end of the armature-lever is brought into contact with the stop m, and the connection between the spring s and arm a is broken, so that a current from the battery E B flows through the wire e, stop m, spring s, wire f, rheostat R h, and wire d', and through the relay R to the ground, the circuit being completed by the current which flows through the wires e' and f' from the battery to the ground. The current which enters the coils of the relay from the equalizing-battery E B is of opposite polarity from that which flows in the same direction from the main battery M B at the home station, and the resistance R h is so proportioned as to make both currents of equal strength, so that the effect of one current on the relay

is neutralized by that of the other. Hence, owing to the fact that these two equal but opposing currents are caused to simultaneously enter the coils of the home relay in the same direction, and to be drawn off simultaneously, the relay is not affected in any way by the action of the home transmitter, but responds only to currents sent over the line from the battery at the distant station, and so records signals only from the transmitter at that station, the main batteries at the two stations, of course, having their opposite poles to the line. Hence the incoming current from the main battery at the distant station passes to the ground through the home relay in the same direction and with the same polarity as the current from the home relay.

I prefer to put on the wire b' a small resistance-box, r , presenting to the incoming current a resistance equal to that which it has to overcome in passing through the main battery M B when it flows over the wire b . A similar resistance, r' , may also be put on the wire e' , for use in connection with the battery E B.

In the modification, Fig. 2, the principle of the invention and the method of operation are the same as described above; but the construction of the transmitter is somewhat changed, two electro-magnets, or two sets of electro-magnets, being combined with two independent armatures, a a' , so as to cause the short-circuiting of the two batteries M B and E B, instead of throwing them out of circuit when the transmitter is opened, as in the arrangement described above. The pivoting-point of the armature a' is connected through the wire b with the main battery M B, and through the wires d d' with the relay, while the line-wire, also leading to said battery, is connected through the wire b' with a stop, against which the armature a' bears when the transmitter is open. The equalizing-battery E B is grounded through the wire f' , and connected, through the wire f , rheostat R h , and wire d' , with the relay, as before, and is also connected through one wire, e , with the pivoting-point of the armature a , and through another wire, e' , with a stop, against which the said armature bears when the transmitter is open. When the transmitter T is open, therefore, the main battery M B is short-circuited through the wire b' , armature a' , and wire b , while the battery E B is short-circuited through the wire e , armature a , and wire e' . When the transmitter T is closed, however, and the short circuits opened, a current from the battery M B flows to earth through the coils of the relay, while a current of equal strength, but of opposite polarity, from the battery E B simultaneously enters

the coils of the relay in the same direction, and so neutralizes the effect of the current from the main battery.

It will be observed that in both modifications the adjustable rheostat or resistance-box R h is never thrown out of circuit, and no matter whether the transmitter throws the equalizing-battery in or out of that circuit, the continuity of such circuit, so far as the rheostat R h is concerned, is never interrupted, and an equal resistance is presented to the incoming current under all circumstances. In the arrangement shown in the diagram Fig. 1, for instance, the rheostat R h has always a ground-connection through the wires f and f' , whether the armature-lever of the transmitter be in the position shown, or be closed to throw the battery E B in circuit. Hence that portion of the incoming current which passes from the wire d to the wire f always meets the same amount of resistance under all circumstances.

I claim as my invention—

1. A station for a duplex-telegraph system in which line-wire, transmitter, main battery, and ordinary relay between said battery and the ground are combined with an equalizing-battery of opposite polarity and a resistance and circuits, substantially as described, whereby the opening of the home transmitter throws the main battery off the line, while the closing of the said transmitter throws the said battery on the line and grounds it through the home relay and simultaneously throws a current from the equalizing-battery through the same coils of the relay in the same direction.

2. A duplex-telegraph system in which the relay is between the main battery and the ground at each station, and the main batteries at the two stations have opposite poles to the line, whereby the main battery at one station passes to the ground through the home relay in the same direction and with the same polarity as the incoming battery from the distant station.

3. In a duplex-telegraph system, the combination of line-wire, transmitter, main and equalizing batteries, relay, rheostats r and r' , and circuits, substantially as described, to present to the current from the distant station resistances equal to the internal resistance of said batteries.

In testimony whereof I have signed my name to this specification in the presence of two subscribing witnesses.

GARRET S. MOTT.
